Max Buck,
by Sam Middleton Donaldson ^{Atty.}

UNITED STATES PATENT OFFICE.

MAX BUCH, OF JACKSON, MICHIGAN, ASSIGNOR TO HENRY E. EDWARDS, OF JACKSON, MICHIGAN.

HOOD OR COVER FOR VEHICLES.

1,219,807.

Specification of Letters Patent. Patented Mar. 20, 1917.

Application filed December 3, 1915. Serial No. 64,901.

To all whom it may concern:

Be it known that I, MAX BUCH, a subject of the Emperor of Germany, residing at Jackson, Michigan, have invented certain new and useful Improvements in Hoods or Covers for Vehicles, of which the following is a specification.

My present invention relates to improvements in tops, hoods or covers designed for use on vehicles of any kind, motor boats and so forth and has for its object to provide an extremely simple and efficient arrangement of the bows and links or levers whereby a uniform movement of the front and intermediate bows will be secured, the top be capable of being extended or collapsed by a single operator and this without disturbing the occupants of the vehicle.

With these and other objects in view the invention includes the novel features of construction and arrangement and combination of parts hereinafter described and particularly defined by the appended claim.

An embodiment of my invention is illustrated in the accompanying drawing, in which,

Figure 1 is a view of the cover or top in its extended or unfolded position.

Fig. 2 is a view of the same with parts in position assumed approximately midway of the folding or collapsing movement.

Fig. 3 is a view of the top completely folded.

Referring by reference characters to this drawing, 1 designates the main bow, which preferably is provided with angular extensions 1^a, provided with openings 1^b, designed to receive the pintle of the usual brackets by which the top is pivotally supported from the vehicle. A rear bow 2 has its ends pivotally connected to the extremities of the extension 1^a as indicated at 2^a. The numeral 3 designates the intermediate or auxiliary rear bow; the numeral 4 the intermediate or auxiliary front bow and the numeral 5 the front or outrigger bow, these all being connected to and supported from the main bow in the manner, which will now be described in detail.

It will be understood that the arrangement of the arms of the bows and the connecting links, levers or braces on opposite sides of the top are identical so that a description of one side answers for both.

Referring now to one side, it will be seen that the outrigger bow has the rear end of each arm pivotally connected by a link or lever 7 with the corresponding arm of the main bow 1 by a suitable pivot indicated at 1^c, said link or lever being extended in rear of its pivot as indicated at 7^a and being pivotally connected at 9^a to one extremity of a link 9, the other extremity of which is pivotally connected at 9^b to the corresponding arm of bow 3.

The adjoining ends of the arm of outrigger bow and link or lever 7 are preferably curved upwardly and pivoted together at 5^a.

A brace or link 8 has its (preferably) downwardly curved end pivotally connected to the side of the main bow 1 at a point 8^a above the pivot 1^c and its forward extremity pivotally connected to the side of the outrigger bow at a point such as 8^b in advance of the pivot 5^a.

The front supplemental or auxiliary bow 4 has its sides or arms pivotally connected to the arms of the outrigger bow at 4^a, these arms being preferably curved as shown at 80 their connecting ends, and said arms of the front auxiliary bow 4 above their pivots 4^a are connected by links 10 with intermediate portions of the links 8.

The forward ends of links 10 are preferably curved upward to their point of pivotal connection as indicated at 10^b and the links 8 preferably have curved portions 8^c which serve to offset the pivots 10^c from the links or braces 8.

A pin 11 on each lever or link 7 serves as a stop to limit the downward movement of brace 8 with relation thereto and hence the downward movement of the outrigger bow.

By reason of the connections thus described the position of the bows when extended is accurately determined while at the same time through the lever members 7 and link 8 and the link 9 acting on levers 7 the upper part of the bows move forward and backward in the folding and unfolding action in an approximately horizontal path, that is without rising or falling until the extreme rear of the vehicle is reached. Thus the top may be folded or unfolded without disturbing the occupants.

Furthermore the top may be easily op-

erated to extend it or to collapse or fold it by a single operator either from within or without the vehicle.

I claim as my invention:

- 5 A vehicle top comprising a rear bow, a main bow, a rear supplemental bow pivoted thereto, a front or outrigger bow, a member pivoted to each side arm of the outrigger bow and main bow, said members having exten-
10 sions, links connecting the arms of the rear supplemental bow with said extensions, a link pivoted to each side of the main bow above said members, and to the outrigger

bow in front of the pivots of said members, a front supplemental bow having its ex- 15 tremities pivoted to the sides of the outrigger bow, and links connecting the sides of the front supplemental bow with said first named links.

In testimony whereof I affix my signature 20 in presence of two witnesses.

MAX BUCH.
